HEAD LAMP WITH LENS RETAINING BAR

Clarence A. Michel, Anderson, Ind., assignor to
General Motors Corporation, Anderson, Ind.,
a corporation of Delaware

Application June 7, 1935, Serial No. 25,393

3 Claims. (Cl. 240—41.5)

This invention relates to lamp structure and more specifically to doorless headlamp structure as applied to motor vehicles.

The type of headlamps used up to the present time have largely been provided with a separate or detachable split or snap rim which surrounded the periphery of the lens and clamped over the forward lamp body to hold the lens in place. With the smaller forward openings in the lamp bodies, and the more streamline shape of the same, the addition of an extra rim has detracted from the appearance and also been more difficult to apply so that it has been desirable to eliminate the same.

15 It is therefore an object of my invention to provide means for securing the lens upon the face of the lamp body without the usual rim. It is a further object to accomplish the above in a simple, economical manner having a pleasing appearance. A still further object of my invention is to eliminate as many of the conventional parts of the lamp as possible and still obtain a satisfactory illumination therefrom.

With these, and other objects in view, the embodiments of my invention are described in the following specification and claims and illustrated in the accompanying drawing in which:

Fig. 1 is a vertical section through a headlamp embodying my invention taken on the line 1—1 of Fig. 2.

Fig. 2 is a front elevation of the headlamp.

Fig. 3 is an enlarged cross section showing the connection between one end of the supporting strap and body.

35 Fig. 4 is a sectional view similar to Fig. 3 of a modified form of my invention.

Fig. 5 is a side elevation of a headlamp showing a still further modified form of my invention, parts being in section.

40 Fig. 6 is a sectional view similar to Figs. 3 and 4 on the still further modified form of connection in line with the embodiment shown in Fig. 5.

Referring specifically to the drawing, a headlamp body 2 is of a parabolic shape having its 45 forward end open and being offset inwardly adjacent said forward portion to form an inwardly directed flange 4 and then continuing forwardly to form a lip 6. Supported upon the lip 6 is a circular gasket 8 having a notch cut in its rear face to fit over the projecting lip 6. On the inside of the lower portion of the casing is placed a reinforcement plate 10 and on the outer face adjacent the same is placed a second plate 12. A series of rivets 14, passing through the second plate 55 in the lower section of the body, holds the whole

assembly together. The central portion of the outside plate 12 is pressed out in spherical form to form a hollow ball 15 having at its lower portion an opening 16 therethrough in which is positioned a hollow bolt 18 for connection to a supporting standard on a car.

Secured under one of the rivets 14 is an angular member 20 which in turn supports a second and longer angular bar 22 whose end portion 24 is in the approximate axis of the parabola and extends rearwardly. Supported on this end 24 is an electric socket 26 which supports the electric lamp 28 at the approximate focus of the parabola. The longitudinal hollow opening 30 in the bolt 18 is provided to carry electrical conductors 32 and in line with this opening is an opening 34 in the body of the lamp in which is placed a rubber grommet 36 and through the center of which pass the same conductors which are connected in the conventional manner to the electric socket 26.

A lens 38 is adapted to enclose the forward portion of the body or housing and has a cut-out groove 40 on its inner face which is adapted to fit over and contacts snugly with the deformable gasket 8. A metal strap 42 is hinged at its top portion to the outside of the casing, as shown at 44, and is adapted to extend vertically down over the outer face of the lens and support the same in contact with the deformable gasket. The lower portion of the strap is bent inwardly to closely follow the outline of the lower edge of the lens and then vertically downward, as shown at 46. A bolt 48 extends through the portion

46 and threadedly engages an angled member 50, which is also secured beneath one of the rivets 14, and extends downwardly parallel to the end 46. It will thus be evident that when the bolt 48 is threaded into the member 50 the strap will be pulled tightly across the face of the lens to hold the same in position. Also located beneath the bolt 48, and adjacent the projected lip 46, is an angled member 52 which follows the contour of the lower portion of the strap up to the lower portion of the lens. It then projects upwardly

45 into a notch 54 in the lower edge of the lens which prevents the lens from rotating in its assembled position. It should be noted in this form of my invention that there is no separate reflector provided but the inner surface of the parabolic housing is formed of a polished surface which acts as a reflector and therefore eliminates this part as a separate piece.

In the embodiment shown in Fig. 4, the body of the lamp 2' has adjacent its upper portion a

groove 56, the remainder thereof being substantially the same with the exception of the inwardly directed flange 4' which is not vertical but slightly at an angle. The end of the strap 42' 5 instead of being hinged to the body 2' is bent inwardly to form a lip portion 58 after following the contour of the lens over the top. In this form, if the strap is detached from the body by 10 loosening the bolt 48, it may be entirely disconnected from the body when the lens is removed.

In Fig. 5 is shown a further form of my invention in which a separate reflector is provided and in this form the outside body or casing 60 carries, adjacent its forward open portion, an 15 annular flange 62 within which is positioned a reflector 64. Between the outer peripheral of the flange 66 of the reflector and the annular flange 62 are placed leaf springs 68 which tend to separate the two. Also carried by this peripheral flange 66 and facing forward or outwardly directed is a deformable gasket 70 which is adapted to bear against the rear face of a lens 72. The upper portion of the annular flange 62 has a forwardly projecting lip 74 having an opening 20 therein which interlocks with the upper end of a strap 76. The strap 76 extends downwardly diametrically across the lens 72 and curls under the lower edge of the lens gripping the same. In the lowermost portion is an opening 78 25 through which passes a short angular bar 80 which locks with the same and extends downwardly to support a threaded bolt 82 which engages an angled arm 84 connected to the body to interlock the lower portion of the strap and lens 30 with the body. In this manner the lens is pressed against the deformable gasket 70 and held in close contact with it which action presses the reflector backward within the housing against the spring pressure of the springs 68 to give a tight 35 assembly throughout.

Fig. 6 shows a slightly modified form of connecting the upper portion of the strap to the body of the lamp in a construction similar to that shown in Fig. 5. In this case the strap 76' 40 passes vertically, diametrically across the lens structure and as it passes over the top thereof is offset inwardly, as shown at 86. It then has a reverse bend in it, as shown at 88, to interlock 45

the forwardly extended inturn flange 90 of the body 60'. This, of course, has the same action as the interlocking between the forwardly extending lip 74 and the inwardly projecting end of strap 76, as in Fig. 5. It will, therefore, be 5 seen that I have provided a simple and efficient means for locking a lens structure to a housing by single means which engages over the exterior portion of the lens and only contacts a small fraction of the periphery thereof. Also in this 10 structure I have eliminated some of the conventional parts and imparted their functions to the others.

I claim:

1. In a lamp structure, a parabolic housing 15 having an open end, an inwardly offset forwardly extending flange on the open end, a ring gasket having a circular slot cut therein to fit over the end of the flanged portion and support it on the latter, a lens closure member for the open end and 20 a strap extending diametrically across the outer face of the lens and connected at its ends to the housing to support the lens over the open end against the gasket.

2. In a lamp, a hollow parabolic body having 25 an open end, a lens closure for the open end, a circular member of deformable material between the lens and the front of the body to form a tight joint between the two, a metal strap pivotally secured to the central top portion of the 30 body and extending across the face of the lens and screw threaded means to secure the lower end of the strap to the lower portion of the body.

3. Lamp structure including an open ended 35 casing, a lens seated at its periphery on the margin of the open end of the casing to close the same, lens retaining means comprising a single strap extending across the face of the lens with 40 its extremities secured to the casing adjacent the rim of the lens, a rearwardly opening lamp bulb socket within the casing and a narrow strap supporting said socket and extending inwardly of the casing from one side thereof in spaced alignment with the lens retaining strap for concealment 45 therebehind.

CLARENCE A. MICHEL.
